UNITED STATES PATENT OFFICE.

WILLIAM LINCOLN PAGE, OF MOSELEY, BIRMINGHAM, ENGLAND.

CANISTER AND LIKE BOX OR CONTAINER.

Application filed August 6, 1926, Serial No. 127,690, and in Great Britain February 17, 1926.

This invention has reference to canisters and like boxes or containers.

The invention has for its purpose the provision of an auxiliary or secondary closure device whereby access to the contents of the canister or container may be simply and expeditiously obtained without the necessity for removal of the lid which constitutes the primary closure member.

10 The invention consists in a canister or container having a lid or primary closure member in which is provided a secondary closure device comprising a sector which is movable about a central pivot in the lid, and in relation to a sector-shaped aperture therein, by means of a fingerpiece provided on the movable sector. The movable sector is adapted for a limited rotational adjustment around the inner face of the lid and upon the upper rim of the canister body, and said rim is preferably inturned to ensure an effective seating for the rotatable sector. The fingerpiece may upstand integrally from a side edge of the movable sector so as to project through the sector-shaped aperture in the lid and to frictionally overlie one edge of said aperture when the sector is closed. Alternatively the fingerpiece may project radially from the peripheral edge of the movable sector so as to operate slidably within a peripheral slot in the lid. Preferably the lid or primary closure member is itself rotatable in relation to the canister body, in which case the movable sector constituting the secondary closure device is adapted to cooperate selectively with a plurality of separate compartments provided by upward radial partitions within the canister or container, said partitions being provided for example by a pair of relatively slidable V-shaped members having an interengaging apical joint.

In order that this invention may be clearly understood and readily carried into practice, reference may be had to the appended explanatory sheet of drawings, upon which:—

Figure 1 is an elevation in perspective of a canister having the present improvements applied, the lid being shown removed from the body.

Figure 2 is a plan of the lid.

Figure 3 is an inverted plan of the lid.

Figure 4 is a sectional elevation of the canister in its assembled condition.

Figure 5 is a plan of the body.

Figure 6 is a perspective view illustrating a modified form of the invention.

Figure 7 is a perspective view, and

Figure 8 is a plan, of a further modification.

In a convenient embodiment of the invention, a canister or container *a* of cylindrical form is provided, this canister *a* being fitted with a lid *b* constituting a primary closure member. The body of the canister *a* is of any ordinary or suitable construction, and is conveniently of sheet metal throughout, or of a construction in which a sheet metal base and a sheet metal rim are combined with an intermediate tubular part of compressed paper or the like. The lid *b* is preferably of a flanged sheet metal construction and is rotatably assembled upon the body, the connection being either of a screw-threaded character (as shown in Figure 6) so as to render the lid detachable, or being of a permanent character provided for example (as shown in Figures 1, 4, and 7) by freely rotatable retaining engagement between a plurality of indentations *c* on the lid flange *d* and an external annular rib *e* on the body.

The face of the lid *b* is pierced with a sector-shaped aperture *f* of convenient angular dimension, and a movable sector plate *g* is arranged in cooperation with this sector-shaped aperture so as to constitute a secondary closure device for the canister or container *a*, this sector plate *g* being mounted upon a pivot *h* carried centrally by the lid, and being thereby rotatably adjustable around the inner face of the lid *b* and over the upper rim of the body, which rim may be slightly bevelled or inturned as shown at *i* to insure an efficient seating for the rotatable sector plate. This rotatable adjustment of the sector plate *g* is effected and limited by means of a small fingerpiece *j* (Figures 1 to 6) upstanding integrally from one side edge thereof so as to project through the sector-shaped aperture *f* in the lid and to frictionally overlie one edge of said aperture when the sector plate is closed, or by means of an equivalent fingerpiece *j'* (Figures 7 and 8) projecting radially from the peripheral edge of the sector plate *g* so as to operate slidably within a slot *n* provided circumferentially in the lid flange *d*.

It will be appreciated that the secondary closure device as hereinbefore described pro-

vides a particularly simple and expeditious means of access to the contents of the canister or container *a*, and enables such contents to be withdrawn, either wholly or in 5 part, without removing the lid *b* which constitutes the primary closure member.

The secondary closure device, when used in conjunction with the rotatable lid *b* as also hereinbefore described, is particularly 10 adapted for selective access to graded material or articles enclosed within separate compartments *k* of the canister or container *a*, the separate compartments in this case being preferably provided by means of upper 15 radial partitions *l*, so that on the lid *b* being rotated to set the secondary closure device over any particular compartment, the movable sector plate *g* may then be rotated to open this particular compartment and 20 permit of an article or material of the desired grade being withdrawn therefrom, this withdrawal being effected without either removing the lid *b* or opening any of the other compartments *k*. In the formation of the 25 compartments *k*, the radial partitions *l* may conveniently be provided by a pair of relatively slidable sheet metal members of V formation having an interengaging apical joint *m*.

30 The canister or container as described, whether partitioned or otherwise, is adapted for general use where quick and frequent access to the contents is required. It is however particularly suitable for enclosing 35 powders for culinary or for toilet use, or for enclosing cotter pins, screws, and like small articles used in connection with motor-cars and the like, and when used for these special purposes the partitioned form of 40 canister or container is of particular advantage, as the material or articles may be graded and packed in the separate compartments *k* so that any particular powder or a 45 pin or screw of any desired size can be selected and withdrawn with great facility.

What I claim as my invention and desire to secure by Letters Patent is:—

1. A canister or container which comprises, in combination, a cylindrical body, an 50 inturned upper rim thereon, a lid fitted on

said body to constitute a primary closure and having a sector-shaped aperture, a central pivot in said lid, a sector plate movable about said pivot and in relation to said sector-shaped aperture to constitute a secondary closure, and an operating fingerpiece on said movable sector plate, said sector plate being adapted for a limited rotational adjustment around the inner face of the lid, upon a seating provided by said in-turned body rim.

2. A canister or container which comprises, in combination, a cylindrical body, a lid rotatable thereon to constitute a primary closure and having a sector-shaped aperture, a pair of apically jointed upright V-shaped partitions located within said body to provide four separate compartments therein, a central pivot in said rotatable lid, a sector plate movable about said pivot and in 60 relation to said sector-shaped aperture to constitute a secondary closure, and an operating fingerpiece on said movable sector plate, said sector plate being adapted for a limited rotational adjustment around the inner face of the rotatable lid, upon a seating provided by the upper rim of said body, and being thereby adapted to cooperate selectively with said compartments in the can- 70 ister body.

3. A canister or container which comprises in combination a cylindrical body, upright radial partitions providing a plurality of sector-shaped compartments within said body, a circular lid rotatable upon said body and having a sector-shaped aperture, a central pivot in said lid, a sector plate movable about said pivot and in relation to said sector-shaped aperture to provide a secondary closure device, and an actuating 85 fingerpiece on said sector plate, said lid being rotatable as a whole to set said secondary closure device over any particular compartment to which access is desired, said sector plate being independently rotatable 90 to open or close the compartment selected.

In witness whereof I have hereunto set my hand.

WILLIAM LINCOLN PAGE.
